(57) **CLAIM**

The ornamental design for a buckle for bag, as shown and described.

DESCRIPTION

FIG. 1 is a front, top, and right side perspective view of a buckle for bag, showing the claimed design;
FIG. 2 is a front view thereof;
FIG. 3 is a back view thereof;
FIG. 4 is a left side view thereof;
FIG. 5 is a right side view thereof;
FIG. 6 is a top view thereof;
FIG. 7 is a bottom view thereof;
FIG. 8 is a cross-sectional view taken along line 8-8 shown in FIG. 2;
FIG. 9 is a back, bottom, and right side perspective view thereof;
FIG. 10 is an exploded perspective view thereof;
FIG. 11 is a front, top, and right side perspective view of another embodiment of a buckle for bag, showing the claimed design;
FIG. 12 is a front view of the another embodiment;
FIG. 13 is a back view of the another embodiment;
FIG. 14 is a left side view of the another embodiment;
FIG. 15 is a right side view of the another embodiment;
FIG. 16 is a top view of the another embodiment;
FIG. 17 is a bottom view of the another embodiment;
FIG. 18 is a cross-sectional view taken along line 18-18 shown in FIG. 12;
FIG. 19 is a back, bottom, and right side perspective view of the another embodiment; and,
FIG. 20 is an exploded perspective view of the another embodiment.

(Continued)

The long dash short dash broken lines and arrows shown in FIGS. 2 and 12 are used to identify the cross-sectional view and form no part of the claimed design.
